Carpet Pattern.

ELEMIR J. NEY, OF LOWELL, MASSACHUSETTS,

ASSIGNOR TO THE LOWELL MANUFACTURING COMPANY.

Letters Patent for a Design No. 85, dated July 16, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other fabrics; of which the following is a full, clear, and exact description, reference being had to the accompanying drawings making part of this specification.

Fig. A, in the centre, is a group of leaves, flowers, and sprigs.

Corners 1, 2, 3, 4, when matched, form four irregular solid blocks, surrounded by a number of irregular blocks, the interiors of which are filled with small lines.

C and D, at the sides, when matched, form four irregular blocks, each of which supports a small sprig. These blocks are also surrounded by a number of irregular dotted blocks, each supporting a small sprig.

Figs. E and F, when matched, form figures similar to that formed by C and D of the sides.

The colors employed for the different portions of the design may be varied to suit the taste and wish of the manufacturer.

Claim.

What I claim as my invention, and desire to secure by Letters Patent, is—
The design or pattern for carpets or other fabrics herein set forth.

E. J. NEY.
